UNITED STATES PATENT OFFICE.

HERMANN ACKERMANN, OF MARYSVILLE, KANSAS, ASSIGNOR TO THE
C. F. ZIMMERMANN COMPANY, OF DOLGEVILLE, NEW YORK.

PICK FOR MUSICAL INSTRUMENTS.

SPECIFICATION forming part of Letters Patent No. 593,072, dated November 2, 1897.

Application filed January 29, 1897. Serial No. 621,177. (No model.)

To all whom it may concern:

Be it known that I, HERMANN ACKERMANN, a citizen of the United States, residing at Marysville, in the county of Marshall 5 and State of Kansas, have invented new and useful Improvements in Picks for Musical Instruments, of which the following is a specification.

This invention relates to stringed musical instruments, such as harps, citherns, and the like; and the object of the present invention is to provide novel, simple, efficient, and economical pick mechanism for picking the strings. This object is accomplished in the 15 manner and by the means hereinafter described and claimed, reference being made to the accompanying drawings, in which—

Figure 1 is a sectional elevation of a portion of a stringed musical instrument provided with my invention, and Fig. 2 is a detail transverse sectional view of the same.

In order to enable those skilled in the art to make and use my invention, I will now describe the same in detail, referring to the 25 drawings, wherein—

The numeral 1 indicates a horizontal bar or frame forming part of a stringed musical instrument and located above the strings 2. The bar or frame is composed of two side 30 parts, (best seen in Fig. 2,) between which are arranged in inclined planes a plurality of pick-bars 3, which are guided through the medium of transverse guide-pins 7 near the lower ends of the pick-bars. The upper ends 35 of these bars are pivoted, as at 6, to the central portions of finger-levers 4, having one extremity pivoted to the bar or frame 1, as at 5. The finger-levers normally stand in inclined planes directly the reverse of the 40 inclined planes in which the pick-bars normally stand in such manner that by depressing the finger-levers the pick-bars will be caused to

move downward in inclined planes. The lower ends of the pick-bars are provided with picking-fingers 9, pivoted to the bars, as at 45 8, and constructed to engage and operate the strings when the bars are depressed and to freely pass by the strings when the bars are elevated. The pick-bars are individually engaged with and operated by independent 50 springs 10, of suitable construction, which serve to elevate the bars after they have been depressed by the finger-levers.

The normal position of the finger-levers is inclined, and as they are pivoted to the inclined pick-bars it is possible to conveniently sweep the fingers over the finger-levers and thus operate the pick-bars to vibrate the strings. Inasmuch as the pick-bars are independently movable through the medium of 55 their respective inclined finger-levers, it is possible to execute various changes or movements in playing the instrument.

Having thus described my invention, what I claim is—

The combination with the bar or frame, and the strings, of a stringed musical instrument, of a plurality of pick-bars extending in inclined planes in the bar or frame, picking-fingers pivoted to the lower ends of the pick-bars, finger-levers extending in inclined planes the reverse of the pick-bars, and pivoted to the bar or frame and to the pick-bars, and springs acting to elevate the pick-bars 70 after they have been depressed by swinging 75 the finger-levers, substantially as and for the purposes described.

In testimony whereof I have hereunto set my hand in the presence of two subscribing witnesses.

HERMANN ACKERMANN.
